Application November 19, 1943, Serial No. 510,879

13. Claims. (Cl. 80—14)

This invention relates to reducing mills for reducing metal tubes and bars; and more particularly to step-by-step reducing mills of the pilger type, that is, mills in which the workpiece reciprocates between gapped die rolls which rotate continuously in one direction about fixed axes, the die rolls reducing the workpiece during its successive strokes in one direction and leaving it free during its non-working return stroke and the workpiece being given an increment of feed and a partial turn for each complete reciprocation, and to a mill of this type in which the reciprocating movements of the workpiece, and also of the mandrel in a tube reducing mill, are under control of positively operated driving means other than the rolls during both the working and return strokes.

The invention has been made especially for the purpose of providing an improved mill for reducing metal tubes in the cold state, but mills according to the invention may be used also for hot reduction of tubes, and features of the invention are adapted for both hot and cold reduction of bars and rods.

The efficiency and capacity of pilger mills depend primarily on the operating speed of which they are capable without impairment of smooth operation. In the conventional pilger mills used for hot working, the workpiece is moved on the working stroke by the die rolls against the pressure of a spring or a fluid-pressed piston, and when the workpiece is free from the rolls at the end of the working stroke, it is given its return movement by the spring or fluid-pressed piston, and at the beginning of each working stroke the rolls grip the workpiece while it is stationary. There is, therefore, a considerable shock on the impact of the die rolls on the stationary workpiece, and objectionable shock results also from the sudden stopping of the workpiece and the mandrel at the end of the return stroke. If the workpiece were cold, these shocks would cause such rapid impairment of the dies and injury to the workpiece that use of such mills for cold reduction would be quite impractical unless the mill were run too slowly for practical commercial use.

To avoid these shocks in the operation of a pilger mill, the workpiece must be started in motion at the beginning of the working stroke and its speed brought up to approximately the pitch line speed of the die grooves of the rolls before the work-piece is engaged by the rolls, and its motion must be reversed without shock at the end of each stroke. The workpiece and mandrel

must, therefore, be under control of a suitable driving mechanism, and, being under control of the driving mechanism, the speed at which the workpiece is driven during that part of the working stroke in which the rolls are in engagement with the workpiece must be maintained approximately equal to the pitch line speed of the die grooves.

The object of the present invention is, therefore, to avoid these shocks and to provide a reducing mill which, when used for cold working, may be operated at comparatively high speeds. To this end, the invention comprises an improved driving mechanism whereby the workpiece, and also the mandrel in a tube reducing mill, are driven at a uniform speed which is approximately the pitch line speed of the die grooves of the rolls during a major portion of both the working and return strokes, and their movement reversed between the strokes with symmetrical deceleration and acceleration, and whereby at the beginning of each working stroke the speed of the workpiece is brought up to approximately the pitch line speed of the die grooves before the workpiece is engaged by the rolls. The operation of the mill is, therefore, such that shock from impact of the dies on the workpiece and from sudden stoppage of reciprocating parts at the end of the strokes in either direction are substantially eliminated. Furthermore, due to the decelerating and accelerating movements being symmetrical, the inertia effects at the end of stroke can be balanced by suitable counter-balancing means. This is of special importance in comparatively large and heavy mills.

In a mill having the new driving mechanism, the workpiece, and the mandrel in a tube reducing mill, are driven at a uniform speed which is approximately the pitch line speed of the die grooves of the rolls during the major portion of the strokes in each direction by segmental gear and rack driving means, and the deceleration, reversal and acceleration between strokes is effected by crank pin and follower-cam means. In a driving mechanism of the form now considered best and as now made, the segmental gear and rack means comprises a horizontally reciprocating rack member with teeth top and bottom and two interrupted, or segmental gears, or pinions driven to move the reciprocating rack member in opposite directions, and the crank pin and follower-cam means comprises a cross-head forming part of or otherwise connected to move with the reciprocating member and having two spaced vertical open-ended cam slots or

grooves and a coating crank the axis of rotation of which extends at right angles to the direction of movement of the reciprocating member and the crank pin of which engages in the slots of the crosshead to effect harmonic motion reversal of the reciprocating member at the end of its movement at uniform velocity in each direction. The segmental gears are driven at the same R. P. M. as the die rolls. The crank pin has a radius twice that of the segmental gears and is driven at the same R. P. M. Therefore, when the crank pin is 30° from the horizontal, the horizontal component of the crank pin velocity is equal to the pitch velocity of the pinions. The slots of the crosshead are of such length and so positioned on the reciprocating member, and the crank shaft is so positioned with relation to the segmental pinions, that during the 60° movement of the crank pin from 30° above to 30° below the horizontal and during its 60° movement from 30° below to 30° above the horizontal, the crank pin will be moving in one of the slots and harmonic reversal of the movement of the reciprocating member will be effected by cooperation of the crank and crosshead. Reversal at each end of travel of the reciprocating member takes place during 60° of the cycle, or $\frac{1}{6}$ of the period of one revolution of the die rolls, and the reciprocating member is driven at uniform velocity in each direction during 120° of the cycle, or $\frac{1}{3}$ of the period of one revolution of the die rolls, the cycle being completed in 360°. The crank pin is out of engagement with the crosshead except at and near the ends of travel of the reciprocating member.

The action of the mechanism is very smooth, there being no impact or inequality of motion when control of the movement of the reciprocating member is shifted from the pinions to the crank or from the crank to the pinions. The workpiece, and the mandrel in a tube mill, are given their reciprocating movements by the reciprocating member of the driving mechanism through suitable connections such that the movement at uniform velocity during 120° of each cycle will be at a speed approximately that of the pitch line of the grooves of the rolls, and, the grooves of the rolls extending over not more than 120° of the circumference of the rolls and the parts being properly timed, the operation of the mill is without harmful shock on engagement of the die rolls with the workpiece or at the end of the strokes. Reversal of the reciprocating movements of the workpiece and mandrel and associated parts is effected without harmful shock even in a comparatively heavy mill operating at comparatively high speed.

A full understanding of the invention can best be given by a detailed description in connection with drawings illustrating an embodiment of the invention in the form now considered best, and such a description will now be given in connection with the accompanying drawings, in which:

Fig. 1 is a plan view of a tube reducing mill embodying the invention;

Fig. 2 is a side elevation of the mill;

Fig. 2a is a continuation of Fig. 2;

Fig. 3 is an enlarged sectional view of the new driving mechanism for reciprocating the tube and mandrel taken on line 3-3 of Fig. 4;

Fig. 4 is a sectional view taken on line 4-4 of Fig. 3;

Fig. 5 is a sectional view on a larger scale taken on line 5-5 of Fig. 3;

Fig. 6 is an end view on a larger scale looking from the right of Fig. 3; and

Fig. 7 is a diagram illustrating the cycle of operations of the new driving mechanism.

The tube reducing mill shown by Figs. 1 and 2 of the drawings is a single mill similar in its principal operating parts other than its reciprocating driving mechanism to the duplex tube reducing mill for which I have filed an application for Patent Serial No. 442,769, filed May 13, 1942. The present invention is in certain respects an improvement on the tube reducing mill of said application, the invention having been made especially with the idea of making it possible to operate a comparatively large heavy powerful mill at comparatively high speed without loss of the desired smoothness of operation, and to obtain closer synchronization of speeds.

Referring to the drawings, and first to Figs. 1 and 2, the mill shown comprises a roll stand 10, a mandrel reciprocating and turning unit 11, a tube reciprocating, turning and feeding unit 12, tube feeding mechanism 13, tube and mandrel reciprocating driving mechanism 14 and an exit tube reciprocating and turning unit 15.

The roll stand comprises a pair of overhung gapped working or die rolls 20 fast on the ends of shafts journaled in a massive frame or housing 22. A pair of overhung stress-balancing rolls 24 (one of which shows in Fig. 1) of the same diameter as the die rolls are fast on the roll shafts at the opposite side of the housing from the die rolls, and there is an overhung backing roll 26 for each of the die rolls and for each of the stress-balancing rolls. At the entrance side of the housing there is a clamping device 27 which is open during operation of the mill and is closed to clamp the rear end of a partially reduced tube when the mill is stopped.

The operating parts of the mandrel reciprocating and turning unit 11 are mounted in a stationary housing 30 seated on the rear end of a longitudinally extending base 31. These operating parts are driven by a transverse driving shaft 32 which is oscillated by the reciprocating mechanism 14. A lever arm 33 fast on shaft 32 reciprocates the mandrel bar 40, which has at its forward end a tapered mandrel. The mandrel bar extends through and is detachably secured by means of a clamp 41 to a longitudinally reciprocable and axially rotatable sleeve 42 the forward end of which is rotatably connected to a sliding member 43 which is reciprocated by the arm 33 through a link 44.

A longitudinal rock shaft 50 which extends forward from one side of the mandrel unit housing 30 is oscillated by the drive shaft 32 through a bevel segment gear 52 on the drive shaft, meshing with a bevel pinion 53 on shaft 50.

The tube reciprocating, turning and feeding unit 12 comprises a housing 60 mounted to slide on the base 31 between the position shown by full lines in Figs. 1 and 2 and that indicated by dotted lines in Fig. 2. The rear end of the tube T is detachably secured by a clamp 61 to the forward end of a longitudinally reciprocable and axially rotatable sleeve 62 through which the mandrel bar extends. The rearward end of sleeve 62 is connected to a sliding member 63 which is connected by a link 64 to a lever arm 65 extending from a pivotally mounted hub 66. This hub carries also a bevel gear segment 67 which meshes with a bevel pinion 68 carried by a sleeve which is slidable on the shaft 50 and is splined thereto so as to be turned therewith, and

which is also mounted in a bearing, 69, on the housing, 60, by which it is held against movement longitudinally with respect to the housing. By oscillation of the shaft, 50, therefore, the arm, 65, is oscillated and the sleeve, 62, and the tube, 5, secured thereto is reciprocated. The arm, 65, of the tube unit and the arm, 33, of the mandrel unit have the same angular motion and are of the same effective radial length and are driven in unison, so that the tube and mandrel are given equal and synchronous reciprocations.

During each non-working forward stroke of the tube and mandrel, the tube unit housing, 60, is given a short forward feeding movement by which the tube is given an increment of feed with respect to the mandrel. This step-by-step forward feeding of the tube unit is effected by a pinion, 70, driven through a one-way clutch of the tube feeding mechanism, 13, from a shaft, 71, the pinion meshing with a rack, 72, extending backward from the tube unit housing through a guide opening in the stationary housing, 39, of the mandrel unit. This pinion and rack serve also for giving a quick return movement to the tube unit when, after being disconnected from a nearly completed tube, it is to be moved back for the positioning of a new tube, the pinion being then disconnected from the one-way feeding clutch and being driven by a motor, 75, which is under push button control. The shaft, 71, is oscillated by the drive shaft, 32, through a segment gear, 73, on the drive shaft which meshes with a bevel pinion, 74, on shaft, 72.

As the reduced portions of the tube advance beyond the die rolls, they are engaged by a friction clamp, 80, of the exit tube reciprocating and turning unit, 15. This friction clamp permits slippage under the increment of feed of the new tube during each non-working stroke, and slippage during the working stroke due to the elongation of the tube. The exit tube unit, 15, comprises a stationary housing, 81, in which is mounted a longitudinally reciprocable and axially rotatable sleeve, 82, which carries the friction clamp, 80, and which is reciprocated in unison with the sleeve, 62, of the main tube unit by means of an oscillating lever arm, 83, connected by a link, 84, to a sliding member, 85, connected to the sleeve, 82. The hub of the lever arm, 83, carries a bevel gear segment, 86, which meshes with a bevel pinion, 87, fast on a shaft, 88, which is connected with and oscillated by the rock shaft, 50.

In the operation of the mill, after each working stroke of the tube and mandrel, during which a length of the tube is pressed between working portions of the grooves of the die rolls, the tube is released by the die rolls and the tube and mandrel then make a forward return stroke, during which they are given a partial turn and the tube unit housing, 60, is moved forward to give an increment of feed to the tube. When the housing, 60, has been advanced to its extreme forward position, as shown by full lines in Figs. 1 and 2, the mill is stopped and the unreduced rear end of the tube is clamped by the clamp, 27. The sleeve, 62, of the tube unit is then disconnected from the tube and the mandrel bar is disconnected from the sleeve, 42, and the housing, 60, is moved backward to its extreme retracted position indicated by dotted lines in Fig. 2, and the mandrel bar is drawn back, by suitable means, not shown, until the forward end of the mandrel is back of the tube clamp of the retracted tube unit. A new tube may then be brought into position in the mill and its rear end secured by

the clamp, 64, and when the mandrel bar has been returned to operative position and connected to sleeve, 42, the mill may again be started in operation.

The mill as so far described is more fully shown and described in my said application Serial No. 442,769, with this principal difference, however, that the mill of said application is a duplex mill which operates on two tubes at the same time, having die rolls on each side of the roll stand housing instead of die rolls on one side and stress-balancing rolls on the other side as herein shown, and having two longitudinal rock shafts like the shaft, 50, one on each side of the base, 31, and tube and mandrel gripping and operating parts on each side of the mandrel and tube units. The construction of the single mill illustrated herein is obviously such that the design could, if desired, be converted to a duplex mill.

The reciprocating driving mechanism, 14, for oscillating the shaft, 32, by which the mandrel-reciprocating sleeve, 42, and the tube-reciprocating sleeve, 62, are reciprocated, comprises a reciprocating member, 90-91, made up of a rack member, 90, and a crosshead, or follower cam member, 91. The rack member is mounted to slide in a housing, 92, mounted on a base, 93, and has two racks, 94 and 95, on opposite sides thereof. The crosshead member, 91, is slidably mounted on a slide way, 96, on a stand, 97, mounted on the base, 93. The member, 90-91, is driven during the major part of its reciprocating movements in each direction by two segmental gears, or pinions, 100 and 101. Pinion, 100, engages the upper rack, 94, to drive the member to the left in Figs. 3 and 4, and pinion, 101, engages the lower rack, 95, to drive the member to the right. The pinions are mounted fast on shafts, 102 and 103, which are journaled in bearings, 104, and each of which is driven by the main mill motor, 105, through a right angle speed reducing unit, 106, and a gear stand, 107. This motor drives also the die rolls through a right angle speed reducing unit, 108, and through a gear stand, 109, from which shafts, 110, one of which shows in Fig. 1, extend to the die roll shafts. The pinions, 100 and 101, both rotate in the same direction, and are driven at the same R. P. M. as the die rolls.

The gear segments of pinions, 100 and 101, are of such angular extent that each pinion, by engagement with its rack, moves the member, 90-91, during 120°, or one-third, of revolution, except for a brief interval of disengagement during which the movement of the reciprocating member is maintained as hereinafter explained, and the relative angular setting of the pinions is such that when either pinion is in engagement with its rack, the other pinion is out of engagement, and that both racks are free from the pinions during 60° of revolution of the pinions, or one-sixth of a cycle of operation, at the end of movement of member, 90-91, in each direction.

A crank, 120, the radial length of which is twice the pitch line radius of the gear segments of pinions, 100 and 101, and which is driven at the same R. P. M. as pinions, 100 and 101, cooperates with the crosshead, 91, to decelerate, reverse and accelerate the movement of member, 90-91, during the 60° of revolution when the racks are free from the pinions. The crank is fast on a shaft, 121, journaled in an upward extension of stand, 97, the axis of which shaft extends at right angles to the direction of movement of member, 90-91, and, most desirably and as shown, cuts a line extending midway between the pinions.

100 and 101. The crank shaft is driven from the gear stand 107, and the direction of rotation of crank 120 in the mill shown is opposite to that of the pinions.

The crosshead 91 has two straight open-ended vertical slots 122 and 123. These slots are spaced such distance apart, and are of such length, and the crosshead is so positioned with relation to the crank shaft 121, and the crank is so positioned angularly with relation to the segmental pinions, that the crank pin 125 engages vertical slot 122 when at 30° above the horizontal and after pinion 100 has ceased to exert moving force on member 90-91 by engagement with rack 94, and the crank then controls the movement of member 90-91 until, at 30° below the horizontal, the crank pin leaves the slot as pinion 101 comes into engagement with rack 95 on the backward stroke of member 90-91; and after 120° rotation of the pinions and crank, the crank pin, when at 30° below the horizontal, engages vertical slot 123 after pinion 101 has ceased to exert moving force on member 90-91 by engagement with rack 95, and the crank then controls the movement of member 90-91 until, at 30° above the horizontal, the crank pin leaves the slot as pinion 100 comes into engagement with rack 94 on the forward stroke.

As the horizontal harmonic motion of the crank pin at 30° from the horizontal either above or below is the same as the uniform motion of member 90-91 when driven by the pinions, there is no impact from inequality of motion when the crank pin engages and disengages the crosshead slots. Member 90-91 is thus driven at uniform velocity during one-third of the cycle in each direction and its motion is reversed with harmonic motion at each end of travel during one-sixth of the cycle, and the transition from uniform speed to harmonic reversing motion is accomplished smoothly without shock and vice versa.

In order that the disengagement of the pinion teeth from the rack shall be without interference, the crosshead slots on their entrance ends are extended to serve as uniform velocity cams for maintaining the uniform speed of the reciprocating member during the time that the pinion teeth are getting clear from the rack teeth. If the pinion segments were made of a total length sufficient to maintain the uniform velocity drive of the reciprocating member during the whole 120° of revolution of the pinions, then when the crank pin took command of the movement of the reciprocating member and began immediately to slow it down there would necessarily be interference between the receding pinion teeth and the rack. To avoid this, the pinion segments are shortened at the recess end to an extent such that full speed drive of the reciprocating member by each pinion ceases at about 8½° before the pinion has made a full 120° driving movement and before harmonic motion by the crank begins, and the crosshead slots have extensions at their entrance ends curved to serve as uniform velocity cams during the 8½° intervals after the pinions have ceased to exert force on the reciprocating member and before the harmonic motion begins. It is not necessary, but for symmetry the slots are most desirably similarly extended at their leaving ends as shown.

The cycle of operations as above described is shown diagrammatically by Fig. 7.

For driving the oscillating driving shaft 32 by which the mandrel-reciprocating member and

the tube-reciprocating member are driven, the reciprocating member 90-91 is connected by a link 130 to a rocking lever arm 131 carried by a rock shaft 132 which is in line with shaft 32 and is connected thereto by a sleeve coupling 133. The lever arm 131 is of such length according to the length of the reciprocating movements of the member 90-91 that the oscillations of shafts 132 and 32 will be of such angular extent that the mandrel- and tube-reciprocating members 42 and 62 will be given reciprocations of the desired length, that is, that on each working stroke and on each return stroke they will be moved at substantially uniform velocity approximately equal to the pitch line speed of the dies during 120° of rotation of the die rolls and will be decelerated, reversed, and accelerated during 60° at each end of stroke. The timing adjustment of the segmental pinions 100 and 101 and crank 120 must, of course, be such that the mandrel bar and tube will be given their uniform velocity movement on the working stroke during the time that the dies are in engagement with the tube.

For changing the amplitude of the oscillations of shafts 132 and 32, and thereby varying the length of stroke given to the tube and mandrel bar for operating the mill with die rolls of different diameters, provision is made for changing the effective radial length of the lever arm 131. For this purpose, the end of link 130 and the end of the lever arm have two or more, two as shown, sets of holes for the connecting pivot pin 134. By shifting the pivot pin from the upper holes in which it is shown to the lower holes 135, the effective length of the lever arm is reduced, and thereby a greater oscillation is given to the shafts 132 and 32. As in the mill of my said application Serial No. 442,769, the points of pivotal connection between the lever arms 33 and 65 and the links 44 and 64 of the mill shown by the drawings of this application are adjustable for varying the effective radial length of these lever arms. This provides for sufficient adjustment of the length of stroke of the tube and mandrel bar for operating with die rolls of a certain difference in diameter. Changing the pivotal connection between the link 130 and the lever arm 131 widens the range of adjustment, thus providing for the use of die rolls of greater difference in diameter.

The mill is most desirably, though not necessarily, provided with counterbalancing means for balancing the inertia effects of reciprocating parts at the ends of the strokes by cushioning the decelerating forces and absorbing energy during deceleration of the parts and returning energy to the reciprocating parts during acceleration. The counterbalancing means may be applied to different reciprocating parts of the mill, and counterbalancing means of different kinds may be used. In the mill shown, air-cylinder compensating means are used. Most desirably, and as shown, the mill is provided with a pair of air cylinders 140 for counterbalancing the reciprocating member 90-91, the rod 141 from the pistons of which is connected to the crosshead 91, and with a pair of air cylinders 142 and 143 the piston rods 144 and 145 of which are connected by links 146 and 147 to short arms extending from the hub of the oscillating lever arm 33 of the mandrel unit 11, and with a pair of air cylinders 150 and 151 the piston rods 152 and 153 of which are connected by links 154 and 155 to short arms extending from the hub of

the oscillating lever arm 83 of the exit tube unit 15.

The tube and mandrel bar steadyng devices 160 and 161 partly shown on a small scale in Figs. 1 and 2 are fully illustrated and described and claimed in my application Serial No. 520,022, filed January 28, 1944.

It is to be understood that the invention is not limited to the exact construction, arrangement and combination of parts shown and to which the foregoing description has been largely confined, but that it includes changes and modifications thereof within the claims.

What is claimed is:

1. In a pilger mill of the type having gapped die rolls mounted to rotate continuously in one direction about fixed axes to work on successive portions of a reciprocating workpiece on successive reciprocations, the improvement which consists in providing driving mechanism for reciprocating the workpiece comprising a rack member, two segmental gears for driving the rack member in opposite directions at uniform speed during a major portion of its reciprocating movement in each direction, a transversely slotted crosshead connected to move with the rack member, a crank for cooperating with the crosshead to reverse the movement of the rack member and crosshead when the rack member is free from the segmental gears at each end of movement.
2. In a pilger mill of the type having gapped die rolls mounted to rotate continuously in one direction about fixed axes to work on successive portions of a reciprocating workpiece on successive reciprocations, the improvement which consists in providing driving mechanism for reciprocating the workpiece comprising a rack member, two segmental gears driven at the same R. P. M. as the die rolls for driving the rack member in opposite directions at uniform velocity during a major portion of its reciprocating movement in each direction, a crosshead connected to move with the rack member having two spaced cam slots extending at right angles to the direction of movement of the crosshead and rack member, and a crank for cooperating with the crosshead to reverse the movements of the rack member during 60° of revolution when it is free from the segmental gears at each end of movement, the crank having a length equal to twice the pitch line radius of the segmental gears and being driven at the same R. P. M. as the segmental gears, and the cam slots of the crosshead being of such length and so positioned and the crank shaft being so positioned with relation to the segmental gears that the crank pin will move through each of the slots during its movement from 30° on one side of a line extending through the axis of rotation of the crank to 30° on the other side of said line, and each of the slots having an extension at its entrance end curved to serve as a uniform velocity cam for maintaining the uniform speed of the rack member for a brief interval while the segmental gear which has been driving the rack member clears from the rack, whereby the workpiece is driven in each direction at approximately the pitch line speed of the grooves of the die rolls during one-third of the cycle and its movement is reversed with symmetrical deceleration and acceleration during one-sixth of the cycle at each end of movement.
3. In a pilger mill of the type having gapped die rolls mounted to rotate continuously in one direction about fixed axes to work on successive portions of a reciprocating workpiece on successive reciprocations, the improvement which consists in providing driving mechanism for reciprocating the workpiece comprising a rack member, two segmental gears driven at the same R. P. M. as the die rolls for driving the rack member in opposite directions at uniform velocity during a major portion of its reciprocating movement in each direction, a crosshead connected to move with the rack member having two spaced cam slots extending at right angles to the direction of movement of the crosshead and rack member, and a crank for cooperating with the crosshead to reverse the movements of the rack member during 60° of revolution when it is free from the segmental gears at each end of movement, the crank having a length equal to twice the pitch line radius of the segmental gears and being driven at the same R. P. M. as the segmental gears, and the cam slots of the crosshead being of such length and so positioned and the crank shaft being so positioned with relation to the segmental gears that the crank pin will move through each of the slots during its movement from 30° on one side of a line extending through the axis of rotation of the crank to 30° on the other side of said line, and each of the slots having an extension at its entrance end curved to serve as a uniform velocity cam for maintaining the uniform speed of the rack member for a brief interval while the segmental gear which has been driving the rack member clears from the rack, whereby the workpiece is driven in each direction at approximately the pitch line speed of the grooves of the die rolls during one-third of the cycle and its movement is reversed with symmetrical deceleration and acceleration during one-sixth of the cycle at each end of movement.
4. In a pilger mill, in combination, a pair of gapped die rolls mounted to rotate about fixed axes, a workpiece reciprocating member, and reciprocating mechanism for driving said member, said mechanism comprising an endwise movable member including a rack portion and a crosshead having two spaced cam slots extending at right angles to the direction of movement of said member, two segmental driving gears for engaging the rack portion of said member to move said member in opposite directions at uniform velocity during the major portion of its reciprocating movement in each direction, a crank which by engagement with the crosshead slots decelerates, reverses and accelerates the movement of said member during 60° of revolution when said member is free from the segmental gears at each end of movement, and means for driving the segmental gears and the crank at the same R. P. M. as the die rolls, the crank being of a length equal to twice the pitch line radius of the segmental gears, and the cam slots of the crosshead being of such length and so positioned and the crank shaft being so positioned with relation to the segmental gears that the crank pin will move through each of the slots during its movement from 30° on one side of a line extending through the axis of rotation of the crank to 30° on the other side of said line.
5. In a tube reducing pilger mill, in combination, a pair of gapped die rolls mounted to rotate about fixed axes, a tube-reciprocating member, a mandrel-reciprocating member, and reciprocating mechanism for driving said members, said mechanism comprising an endwise movable member including a rack portion and a crosshead having two spaced cam slots extending at right angles to the direction of movement of said member, two segmental driving gears for

engaging the rack portion of said member to move said member in opposite directions at uniform velocity during the major portion of its reciprocating movement in each direction, a crank which by engagement with the crosshead slots decelerates, reverses and accelerates the movement of said member during 60° of revolution when said member is free from the segmental gears at each end of movement, and means for driving the segmental gears and the crank at the same R. P. M. as the die rolls, the crank being of a length equal to twice the pitch line radius of the segmental gears, and the cam slots of the crosshead being of such length and so positioned and the crank shaft being so positioned with relation to the segmental gears that the crank pin will move through each of the slots during its movement from 30° on one side of a line extending through the axis of rotation of the crank to 30° on the other side of said line.

6. In a pilger mill, in combination, a pair of gapped die rolls mounted to rotate about fixed axes, a workpiece reciprocating member, and reciprocating mechanism for driving said member, said mechanism comprising an endwise movable member including a rack portion and a crosshead having two spaced cam slots extending at right angles to the direction of movement of said member, two segmental driving gears for engaging the rack portion of said member to move said member in opposite directions at uniform velocity during the major portion of its reciprocating movement in each direction, a crank which by engagement with the crosshead slots decelerates, reverses and accelerates the movement of said member during 60° of revolution when said member is free from the segmental gears at each end of movement, and means for driving the segmental gears and the crank at the same R. P. M. as the die rolls, the crank being of a length equal to twice the pitch line radius of the segmental gears, and the cam slots of the crosshead being of such length and so positioned and the crank shaft being so positioned with relation to the segmental gears that the crank pin will move through each of the slots during its movement from 30° on one side of the line extending through the axis of rotation of the crank to 30° on the other side of said line, and each of the cam slots having an extension at its entrance end curved to serve as a uniform velocity cam for maintaining a uniform speed of movement of said member for a brief interval while the segmental gear which has been driving said member clears from the rack.

7. Reciprocating mechanism, comprising an endwise movable rack member, two segmental gears engaging the rack member to move it in opposite directions during a major portion of its reciprocating movement in each direction, a transversely slotted crosshead connected to move with the rack member, a crank the length of which is equal to twice the pitch line radius of the segmental gears and which cooperates with the slotted crosshead to decelerate, reverse and accelerate the movement of the rack member when it is free from the segmental gears at each end of movement, and means for driving the segmental gears and the crank at the same R. P. M.

8. Reciprocating mechanism, comprising an endwise movable member, two racks on said member, two segmental driving gears for engaging said racks to move said member in opposite directions during a major portion of its

reciprocating movement in each direction, a crosshead on said member having two spaced cam slots extending at right angles to the direction of movement of said member, a crank the length of which is equal to twice the pitch line radius of the segmental gears and which by engagement with the crosshead slots decelerates, reverses and accelerates the movement of said member at each end of movement, and means for driving the segmental gears and the crank at the same R. P. M.

9. Reciprocating mechanism, comprising an endwise movable member, two racks on said member, two segmental driving gears for engaging said racks to move said member in opposite directions during a major portion of its reciprocating movement in each direction, a crosshead on said member having two spaced cam slots extending at right angles to the direction of movement of said member, a crank the length of which is equal to twice the pitch line radius of the segmental gears and which by engagement with the crosshead slots decelerates, reverses and accelerates the movement of said member at each end of movement, means for driving the segmental gears and the crank at the same R. P. M., and counterbalancing means for absorbing energy from said member during deceleration and for returning energy thereto during acceleration thereof.

10. Reciprocating mechanism, comprising an endwise movable member, two racks on opposite sides of said member, two segmental driving gears for engaging said racks to move said member in opposite directions during a major portion of its reciprocating movement in each direction, a crosshead on said member having two spaced straight cam slots extending at right angles to the direction of movement of said member, a crank the length of which is equal to twice the pitch line radius of the segmental gears and which by engagement with the crosshead slots decelerates, reverses and accelerates the movement of said member when it is free from the segmental gears at each end of movement, and means for driving the segmental gears and the crank at the same R. P. M.

11. Reciprocating mechanism, comprising an endwise movable member including a rack portion and a crosshead having two spaced cam slots extending at right angles to the direction of movement of said member, two segmental driving gears engaging the rack portion of said member to move said member in opposite directions at uniform velocity during a major portion of its reciprocating movement in each direction, a crank which by engagement with the crosshead slots decelerates, reverses and accelerates the movement of said member during 60° of revolution when said member is free from the segmental gears at each end of movement, and means for driving the segmental gears and the crank at the same R. P. M., the crank being of a length equal to twice the pitch line radius of the segmental gears, and the cam slots of the crosshead being of such length and so positioned and the crank shaft being so positioned with relation to the segmental gears that the crank pin will move through each of the slots during its movement from 30° on one side of a line extending through the axis of rotation of the crank to 30° on the other side of said line.

12. Reciprocating mechanism, comprising an endwise movable member including a rack portion and a crosshead having two spaced cam slots

extending at right angles to the direction of movement of said member, two segmental driving gears for engaging the rack portion of said member to move said member in opposite directions at uniform velocity during a major portion of its reciprocating movement in each direction, a crank which by engagement with the crosshead slots decelerates, reverses and accelerates the movement of said member during 60° of revolution when said member is free from the segmental gears at each end of movement, and means for driving the segmental gears and crank at the same R. P. M., the crank being of a length equal to twice the pitch line radius of the segmental gears, and the cam slots of the crosshead being of such length and so positioned and the crank shaft being so positioned with relation to the segmental gears that the crank pin will move through each of the slots during its movement from 30° on one side of a line extending through the axis of rotation of the crank to 30° on the other side of said line, and each of the cam slots having an extension at its entrance end curved to serve as a uniform velocity cam for maintaining by cooperation with the crank pin the uniform speed of movement of said member for a brief interval while the segmental

gear which has been driving said member clears from the rack.

13. In a pilger mill, in combination, a pair of gapped die rolls mounted to rotate about fixed axes, a workpiece-reciprocating member, and reciprocating mechanism for driving said member, said mechanism comprising an endwise movable member including a rack portion and a crosshead having two spaced cam slots extending at right angles to the direction of movement of said member, two segmental driving gears engaging the rack portion of said member to move it in opposite directions at uniform speed during a major portion of its reciprocating movement in each direction, a crank the length of which is equal to twice the pitch line radius of the segmental gears and which by engagement with the crosshead slots decelerates, reverses and accelerates the movement of said member, means for driving the segmental gears and the crank at the same R. P. M., and counterbalancing means for absorbing energy from said member during deceleration and for returning energy thereto during acceleration thereof.
